UNITED STATES PATENT OFFICE.

ROBERT HEAD, OF NEW YORK, N. Y., ASSIGNOR TO ROBERT L. WATKINS, OF NEW YORK, N. Y.

MOTION-PICTURE MACHINE.

1,134,611.

Specification of Letters Patent.

Patented Apr. 6, 1915.

Application filed May 26, 1909. Serial No. 498,536.

To all whom it may concern:

Be it known that I, ROBERT HEAD, a citizen of the United States, residing in the city of New York, borough of Manhattan, county and State of New York, have invented a certain new and useful Moving-Picture Machine, of which the following is a specification.

This invention is a machine for making photographic negatives in rapid succession.

The object in view is to provide simple and effective mechanism for securing latent impressions of pictures in rapid succession on a photographic film.

A further object is to enable the machine to be used in connection with a magnifying apparatus or microscope whereby enlarged images may be photographed. A special purpose of this part of the apparatus is to photograph specimens of blood for the diagnosis of diseases.

The invention consists in the construction and combination of parts hereinafter described and claimed.

In the accompanying drawings I have illustrated different practical embodiments of the invention, but the constructions shown therein are to be understood as illustrative, only, and not as defining the limits of the invention.

Figure 1 is a side elevation of my new machine for producing photographic negatives in rapid succession on a movable film, the casing of the machine being shown in section. Fig. 2 is a vertical section on the line 2—2 of Fig. 3. Fig. 3 is an end elevation looking at the right of Fig. 2, a part of the figure being in section and broken away. Fig. 4 and Fig. 5 are views in side elevation and in plan of the shutter mechanism adapted for operation by the means for intermittently moving the film. Fig. 6 is an elevation illustrating my machine in conjunction with a magnifying apparatus. Fig. 7 is a detail section on the line 7—7 of Fig. 1, illustrating the means for intermittently rotating one of the feed spools.

A, designates a suitable supporting frame for the operative parts of the machine, the same being housed or contained within a casing, a, the latter being fastened detachably to a base, a'. The frame is provided with a plurality of top rails, a², which form bearings for shafts, B, C, adapted to carry a supply spool or drum, B', and a winding spool or drum, C'. The spool, B', is not

driven by power, but on the contrary, it rotates idly by a pull upon the film. For restraining the supply spool from too rapid rotation, a suitable brake or tension device, b, is employed, the same being shown in the form of a spring attached to the spool near one end and adapted for engagement frictionally with one of the rails, a².

The winding spool, C', is provided with a pulley, c, adapted to be driven by a belt, D, from a driving pulley, D', the latter being made fast with shaft, D², which is journaled in the frame, A. Said shaft may be rotated in any suitable way, but as shown in Fig. 3, I may employ a crank, d, having a stud, d', adapted to interlock with a notch, d², of shaft, D², whereby the crank is connected detachably to said shaft and said crank operates the shaft only when it is turned in one direction.

E, designates a feed drum or spool adapted to rotate continuously in one direction, said feed drum or spool having teeth, e, which work in perforations provided, in the film, F. The feed drum is carried by a shaft, e', journaled in the frame, A, below supply spool B, and at one end of said shaft, e', is provided a gear, e², which meshes directly with a gear, e³, that is made fast with shaft, D², whereby the shaft is adapted to operate spool, E, through the intermeshing gears, e², e³.

G, designates a take up spool or drum which is carried by a shaft, g, said shaft being journaled in frame, A, below winding spool, C', and parallel to spool, E. The take up spool, G, is provided with teeth, g', similar to teeth, e, of feed spool, E, but while the last mentioned spool, E, rotates continuously, I have provided means for intermittently rotating said take up spool, G, so that it will advance film, F, by an intermittent motion and with intervals of rest or dwell.

The means for intermittently rotating take up spool, G, constitutes an important element of my invention. In the embodiment shown more particularly in Figs. 1, 3, and 7 of the drawings, shaft, g, is extended a suitable distance through one side of frame, A, and mounted rigidly on said extended part of the shaft is the shouldered member heretofore mentioned. Said shouldered member, G, in the form of a disk, H, said disk being provided with a notch, h, which forms a shoulder, h'. Driving mem-

ber, I, in the form of a gear wheel, is mounted loosely on the extended part of shaft, g, and this gear meshes with gear, e³, of driving shaft, D², whereby gear, I, is 5 adapted to turn continuously in one direction when shaft, D², is rotated. Said gear, I, and the disk, H, are operatively connected by a coiled spring, J, the same being fitted loosely on shaft, g, and one end of said spring, 10 J, being attached securely to gear, I, while the other end of said spring is fastened firmly to the shouldered disk, H.

One or more pawls, K, are adapted for coöperation with shouldered disk, H. Each 15 pawl is pivoted to frame, A, by a screw or stud, k, and said pawl is equipped with a releasing stud, k'. The pawls are pressed into engagement with the edge of the disk by springs, K', fastened to the frame, A, 20 and as the disk is turned, said pawls, K, engage successively with the shoulder, h', of said disk, thus restraining the disk from rotating under the action of the spring, J, and through the period when gear, I, is rotated 25 by gear, e³, so as to place said spring, J, under tension.

L designates a trip which is integral with or made fast to gear, I, for rotation therewith, and this trip extends beyond one side 30 of the gear so that it will engage with the releasing studs, k', of pawls, K, successively, thus throwing each pawl out of engagement with the shoulder of disk, H, whereupon the spring, J, operates to turn the disk, H, in one direction until said disk is moved far enough for the next pawl, K, to engage with shoulder, h', of said disk, and thus lock the disk against continued rotation.

The base, a' of the machine is provided 40 with an opening, m, which is adapted to be closed by a door, M, see Fig. 2, said door being preferably movable. In one embodiment of the invention, the door is provided with a lens tube, N, having a lens, n, adapted to project an image against film, F. Said film passes from the spool, B, to and around the continuously rotating feed spool E, thence across to intermittently rotated 45 take up spool, G, and thence up to the positively driven winding spool, C'.

O, designates a guide secured rigidly in the frame back of the film and between spools, E, G. In addition to its function as 55 a guide for the sensitized film, member O serves the further purpose of a background for the film, said member being composed, preferably, of opaque material to preclude the passage of the light rays therethrough. Below this guide and parallel therewith is 60 a guide plate, P, the same being secured firmly in frame, A. One end of said guide plate is curved upwardly at, p, part way round the spool, G, but the other portion of the guide plate is deflected upwardly at, p', 65 near spool, E, and is then curved down-

wardly at, p², below said spool E, all is clearly shown in Fig. 2.

The guide plate is provided with an exposure opening, o, in line with lens, n, and opposite to guide, O, and with this guide 70 and background plate coöperates a shutter, Q, shown in Figs. 2 and 5. Said shutter is provided with an opening, q, adapted to register with opening, o, in the guide plate. As shown in Fig. 5, openings, o, q, are oblong, but they may be of any desired shape, as for example, circular. The shutter, Q, is 75 adapted for reciprocating movement in frame, A, and it is preferred to mount the shutter for sliding movement between guide plate, P, and guide rail, q'. A stud or pin, r, is fastened to the shutter and operates in a slot, r', provided in one side member of frame, A. To this pin, r, is connected one end of a link, R, the other end of which is pivoted at, r², to lever, R'. Said lever is 80 made fast with a driving gear, R², one end of said lever being extended beyond the gear so as to produce a counterpoise, R³. Gear R² is mounted on a short stub shaft, r³, of 85 frame, A, and said gear meshes with a gear, r⁴, which is secured rigidly to shaft, g, of the intermittently operated take up spool, G. It will be seen that shutter, Q, is operated automatically by the means employed 90 for moving the film, F, and when said film is allowed to rest for a short time, the shutter operating means operates said shutter, Q, for moving its opening, q, into and out of register with the exposure opening, o, of 95 guide plate, P, whereby a portion of the film is exposed for the lens to project the image against the sensitized surface of said film.

S, designates a hood, which is secured 100 within the machine and to base, a', thereof. This hood extends from the base toward the shutter, Q, and it precludes rays of light from having access to the lens chamber except through the shutter in the operation of 105 the machine.

While the machine may be employed for 110 general photographic work in taking a succession of pictures rapidly of moving objects, I do not restrict the machine to such use, for the reason that in Fig. 6 I have shown said film exposing machine in connection with a magnifying apparatus, the latter being in a form of microscope. The film exposing machine is shown as resting upon a table, T, and coöperating with base, a', of said machine is a bellows or collapsible chamber, t, the same being adapted to extend into opening, m, and hood, S, of the machine shown in Fig. 2. An observation tube, t', having an eye piece, t², is also disposed for coöperation with hood, S, and in this embodiment of the invention, it is preferred to provide shutter, Q, with a light reflecting surface or medium, such as an 115 opaque layer of white material, like white 120 opaque layer of white material, like white 125 opaque layer of white material, like white 130

enamel, whereby the operator may view the image projected by the magnifying apparatus.

A microscope, U, of any usual or preferred construction, is supported by a stand or table, u, which is separate from the stand, T, of the film exposing machine, whereby the jarring motion of the film exposing machine will not effect or disturb the microscope or the image projected thereby. As is usual in the art, said microscope is provided with a table, u', having means for supporting a microscopic specimen between the lens of said microscope and a source of light, such as an electric light apparatus indicated at V in Fig. 6.

In assembling the structure shown in Fig. 6, the bellows, t, and the film exposing machine are supported on table, T, and observation tube, t', is adjusted into co-operative relation to the hood, S, and the shutter, Q. The microscope is moved for its lens tube to align with the bellows and with the source of light apparatus, V, and when the required specimen is placed on the table of said microscope, the apparatus is ready for use. The light from apparatus, V, is directed through the specimen to be photographed on the microscope, the latter operating to project an enlarged image through bellows, t, and against the movable film, F, of the film exposing machine, whereby enlarged images of the microscopic specimen may be photographed in rapid succession on the film, F.

The operation of exposing a film so as to obtain a number of negatives rapidly, is as follows:—A spool, B', containing a film of the proper kind is placed in the machine for its tension device, b, to engage with frame, A, and said film is adjusted beneath feed spool, E, over the deflected part, p', p'', of the guide plate, across said guide plate, between it and guide, O, thence between spool, G, and curved part, p, of the guide plate, and finally is attached to the winding spool, C'.

The machine may be operated by power of any suitable kind, but when it is equipped with crank, d, said machine is operated by hand. The crank is turned in a direction to rotate shaft, D², thereby making belt, D, rotate the winding spool, C', and gear, e², operates gears, e¹, and I. Said gear, e², drives the spool, E, continuously in one direction, whereas the gear, I, so cooperates with spring, J, disk, H, and pawls, E, as to rotate the take up spool, G, intermittently. The tension of spring, J, on disk, H, tends to turn it in one direction, and the tension of this spring is increased by reason of the fact that said spring is attached to gear, I, which is turned by gear, e³. The tendency of disk, H, to rotate is checked by the engagement of one pawl, K, with the shoulder,

h', of said disk, but when the trip, L, (which rotates with gear, I) engages with a stud, k', of the pawl in engagement with shoulder, h', of the disk, then the pawl is lifted and clears the shoulder, h', whereupon spring, J, acts to quickly turn the disk, H, in one direction and until the next pawl engages with the shoulder, h', of said disk, thereby locking the disk against further movement under the action of the spring. The gear, I, tends to turn by reason of its intermeshing engagement with gear, e³, but the disk, H, cannot turn with the gear or the spring, because it is locked by the second pawl engaging with the shoulder, h', thereof, and thus continued rotation of gear, I, while the disk is locked, places spring, J, under tension. Now, when the disk is free from the restraint of the pawl the spring acts to impel the disk rapidly for a partial turn and as said disk is fixed to the shaft, g, of take up spool, G, said spool is turned quickly for a certain angular distance whereby the film, F, is drawn or fed forward the distance of one negative or photographic exposure. Such exposure of the film is effected by moving shutter, Q, and said shutter is operated while the film is at rest, so that the image will be projected upon the sensitized surface of said film.

It will be observed that the film is engaged with a feed spool, E, and a take up spool, G, the former being rotated continuously and the latter being rotated intermittently. When the take up spool, G, and the film, F, are at rest, the spool, E, continues to turn, and this operation causes the film to become bent, deflected, or arched as indicated at, f, in Fig. 2, whereby a certain amount of slack is produced in the film when the take up spool, G, is not turning. Now, when the spool, G, is turned quickly by spring, J, and the described mechanism, said spool, G, draws the film quickly so as to take up the slack, f, said allowance of slack being made in order that there will be no undue strain or distortion of the film under the almost instantaneous action of the intermittently rotated take up spool.

The mechanism heretofore described is extremely simple in construction and efficient in operation. The parts composing the intermittent feed mechanism act with extreme rapidity to secure rapid intermittent motion of the film, whereby the succession of photographic exposures may be made of a moving object, thus producing a film with latent impressions of said moving object, which film can be developed and fixed in any desired manner.

While the feed mechanism performs a number of operations on the film, said feed mechanism is of so simple a character that it is not liable to get out of order, and experience has shown that it is efficient and

reliable in service. Furthermore, the apparatus is compact in construction, so that it may be carried or transported with ease.

Having thus fully described the invention, 5 what I claim as new, and desire to secure by Letters Patent is—

1. In a photographic apparatus, the combination of means for supporting a sensitized film, means for producing an image 10 on the sensitized surface of the film, a feed roll, a take-up roll, a driving member, means coöperating with the feed roll and the driving member for actuating said feed roll at a constant speed, and means coöperating 15 with the take-up roll for imparting intermittent rotation thereto, said means embodying a shouldered stop member mounted on the spindle of said take-up roll and rotatable with said roll, a plurality of pawls mounted 20 independently of the stop member for engagement with the shoulders on said member, and a power receiving member loosely mounted on said spindle, and rotatable independently of the take-up roll, a tension member mounted intermediate the shouldered stop member and the power receiving member and coöperating with said members whereby the rotation of the power receiving 25 member serves to place the spring under tension while the take-up roll is retained against rotation by the aforesaid circumferentially disposed pawls, and a trip on said power receiving member for engaging said pawls in succession whereby the tension of the tension member is allowed to intermittently 30 revolve the take-up roll.

2. In a photographic apparatus, the combination of means for supporting a sensitized film, means for producing an image on 35 the sensitized surface of the film, a feed roll, a take-up roll, a driving member, means coöperating with the feed roll and the driving member for actuating said feed roll at a constant speed, and means coöperating with 40 the take-up roll for imparting intermittent rotation thereto, said means embodying a shouldered stop member mounted on the spindle of said take-up roll and rotatable with said roll, a plurality of pawls mounted 45 independently of the stop member for engagement with the shoulders on said member, and a power receiving member loosely mounted on said spindle, and rotatable independently of the take-up roll, a tension 50 member mounted intermediate the shouldered stop member and the power receiving member and coöperating with said members whereby the rotation of the power receiving member serves to place the spring under tension 55 while the take-up roll is retained against rotation by the aforesaid circumferentially disposed pawls, and a trip rotatable with the power receiving member 60

for engaging said pawls in succession, whereby the tension of the tension member is 65 allowed to intermittently revolve the take-up roll.

3. In a photographic apparatus, the combination with means for imparting movement intermittently to a sensitized film, and 70 means for projecting an image against the sensitized surface of said film, of a shutter and light-reflecting surface coöperating with the shutter and adapted to be interposed in the path of the projected image whereby the 75 image may be viewed and the object kept in proper focus during the movement of the film.

4. In a photographic apparatus, the combination with means for imparting movement intermittently to a sensitized film, and 80 means for projecting an image against the sensitized surface of said film, of a shutter provided with a light reflecting surface adapted to be interposed in the path of the projected image, and observation means 85 whereby an operator may view the images reflected by said light-reflecting surface so as to enable the object to be kept in proper focus during the movement of the film.

5. In a photographic apparatus, the combination with means for imparting movement intermittently to a sensitized film, and 90 means for projecting an image against the sensitized surface of said film, of a shutter operating to expose the film during the intervals of rest of the shutter, said shutter being provided with a surface adapted to reflect the light, and observation means 95 coöperating with the shutter so that an operator may view the image reflected by said 100 reflecting surface of the shutter and be thus enabled to keep the object in focus during the movement of the film.

6. In a photographic apparatus, the combination with means for imparting movement intermittently to a sensitized film, and 105 means for projecting an image against the sensitized surface of said film, of a shutter operating to expose the film, a light-reflecting surface coöperating with the shutter and 110 adapted to be interposed at intervals in the path of light to the film and to reflect the image, a light-excluding hood in front of the shutter, and an observation tube coöperating with the hood and the shutter 115 whereby an operator may view on the light-reflecting surface the images to be projected on the film and to keep the object in focus during the movement of said film.

In testimony whereof I have signed my 120 name to this specification in the presence of two subscribing witnesses:

ROBERT HEAD.
